UNITED STATES PATENT OFFICE.

ARTHUR SCHULZE, OF BERLIN, GERMANY.

PROCESS AND DEVICE FOR PRODUCING GUILLOCHES AND THE LIKE.

1,391,859.

Specification of Letters Patent. Patented Sept. 27, 1921.

Application filed September 27, 1919. Serial No. 327,012.

To all whom it may concern:

Be it known that I, ARTHUR SCHULZE, a citizen of the German Republic, residing at Berlin, Germany, have invented new and useful Improvements in Processes and Devices for Producing Guilloches and the like, (for which applications have been filed in the following countries: Germany, No. Sch. 53120, VI/57d, filed May 18th, 1918; Austria, A. 3576-18, filed June 24, 1918, and in Russia, No. 72550, filed July 18th, 1917,) of which the following is a specification.

The known process for producing guilloches or rose-engine patterns upon printing plates, especially for the printing of paper currency and the like, consists in guiding a diamond along the sinuous intertwining line which forms the guilloche pattern and in removing the acid proof film along this line preparatory to the etching of the plate. The lines thus drawn with diamonds are extremely fine and hence it is necessary to broaden them. If a printing plate is to be made with the aid of this process for example the design drawn in the film is etched deeply in to the plate and by this means a broadening of the lines to a larger or smaller extent may be effected, although the scope thus afforded is confined to very narrow limits. The machines employed for producing guilloches or rose-engine patterns are very expensive, they are slow in operation and have a number of other draw-backs. The total number of lines required to properly cover a fairly large surface with lines as fine as those resulting in this process is extraordinarily large. As a rule a single diamond only is employed. Machines operating with a plurality of diamonds, two or three for example, have been proposed and tried, but they have not proven a success. Therefore it is necessary to lift the diamond and readjust it for every new line made in tracing the pattern. Even if the adjustment of the diamond and rearrangement of the machine are effected automatically, and if the work is continued without interruption day and night, the ornamentation of a fairly large surface with guilloches takes several days and even several weeks if the design is composed of dense lines. If, for example, a large new pattern, say a large rosette, is to be drawn, the total impression which the pattern will produce as a whole, cannot be

foretold with certainty. It will be necessary either to rest satisfied with a finished unsatisfactory pattern or to repeat the laborious process several times until a satisfactory pattern has been obtained. At present the fine lines which result in such a process enable delicate patterns to be produced that will admit of their employment for paper currency, but they are not without disadvantages. In the first place all the lines are of the same small breadth. A broader line, whether its breadth is to be equal throughout its length, or to become alternately broader and thinner, can only be produced by drawing a number of fine lines so near to each other that they become one during the succeeding etching process. Thus, variety in the breadth of the lines forming the pattern can only be obtained in a round-about way with considerable loss of time. The fact that the delicacy of the drawn lines permits of the drawings being immediately made in the required or original size is an apparent advantage only. In making printing plates for drawings, or in reproducing drawings in any other manner, it is preferable to make the original drawings on an enlarged scale because the inexactitudes and errors in the same are diminished when reproduced on a reduced scale (in engraving work also large stencil-plates are preferably employed from which the patterns are transferred to the actual reduced engraving by means of a pantograph), but for several reasons this plan cannot be adopted at the present time in producing guilloches. The necessity of making the drawings straight away in their usual size is coupled with the disadvantage that the motions which the diamond must describe are all on the same small scale, and consequently inexactitudes and errors in the drawing are unavoidable, no matter how well made and expensive the rose-engine or guilloching machine may be. An indirect consequence of these circumstances is that in the production of paper currency the photo-mechanical processes do not play so important a part and are not used to such an extent as they could be, and that, merely in consequence of these minor circumstances, the photo-mechanical process is not regarded to be of the same value as the other processes in the production of paper currency and is only used for work of minor importance.

With the old process the use of a whole bunch of approximately parallel lines, or of lines which alternately converge toward and diverge from each other, had to be discarded. 5 This is due to the fact that the lines could only be drawn singly, and that for this reason the drawing could not be made accurately enough, especially at points where the interlinear space was very small, so that 10 errors or irregularities cropped up in the drawings which were very perceptible to the eye. On the other hand the employment of bunches of lines that approach each other so as to leave very little space and which are 15 drawn with perfect accuracy is particularly desirable in order to render imitation more difficult. Another point worthy of notice is that, in the case of complicated guilloches at least, only solid or unbroken lines, but no 20 dotted or dash-and-dot lines, which assist greatly in enlivening the drawing and making it more difficult to counterfeit, can be executed with the old process.

The object of the present invention is to 25 provide a means for producing guilloches which is not encumbered with the disadvantages and imperfections of the old process and which permits of the execution, with much simpler and cheaper machines and in 30 a fraction of the time hitherto required, of work which is not only of the same excellence as that performed with the older appliances, but which is distinguished from the older patterns by greater variety, better artistic 35 effects and by its being more difficult to counterfeit. This object is accomplished by a small luminous surface or spot, or any number of such spots, being caused to execute motions, in a dark room opposite to a 40 photographic apparatus and relative to its lens of the kind required for marking out the guilloche. These motions will generally be composed of a number of simple motions. Each luminous image will then describe lines 45 on the sensitive plate similar to those which the diamond executed on the acid-proof film in the old process. The small luminous surfaces may be given the shape of circular disks. Lines will then be produced which are 50 of equal breadth throughout their lengths. If a plurality of small luminous circular surfaces are employed, their diameters may differ so that a number of adjacent lines of various breadths will be obtained. The 55 distances between the neighboring surfaces may be equal or various. If the luminous surfaces measure more in one direction than in another, if for example they take the form of a dash or stripe, lines of continuously 60 varying breadth may be produced. The same pattern may be made in various sizes simply by changing the position of the photographic apparatus without at all altering the illuminating machine or the mechanism 65 which brings about the movements of

the luminous spots. Since any number of luminous spots may act in unison and hence a corresponding number of lines may be simultaneously drawn, a dense pattern composed of a large number of lines may be produced in a very short time, *e. g.* in a few minutes. The movements which the luminous spots and the sensitive plate execute relative to each other may be brought about by moving the luminous spots only, or by 75 only moving the sensitive plate or the lens, or by a combination of these three movements. If the motion is executed only by the luminous spots themselves, the lines or drawing which they themselves actually describe will be as much larger than the scale of the drawing produced on the sensitive plate, as the distance between the plane in which the luminous spots are situated and the lens is larger than the distance between 80 the sensitive plate and the lens. It is therefore possible to have the actual motions executed on an enlarged scale and hence to produce exact drawings or patterns with a machine that is cruder and cheaper than it 90 could be in using the old process. The possibility of producing patterns on any desired scale may be turned to account by first carrying out a guilloche or pattern on the scale on which it is to be employed so as to obtain a proper idea of the impression it will make, and by then producing the same guilloche on a much larger scale so as to be able to insert it in another drawing that has been made on the same larger scale and which, 100 in addition to a guilloche on the larger scale, comprises a number of other designs such as hand-drawn ornaments, letters or figures, or other ground ornaments, which latter may also be produced by the new 105 process. Composite drawings of this kind, enlarged to the extent of three to five times their ordinary size for example, are executed for the purpose of making the printing plate on a reduced scale with the aid of 110 photo-mechanical means. In making such plates with the old guilloche-producing process the guilloches first had to be enlarged with the aid of photographic apparatus, because the production of original guilloches 115 on an enlarged scale was not possible. The possibility of producing the original guilloches on the desired enlarged scale is a great benefit for the improvement of the quality of the drawings. The disadvantage 120 in the old process in this respect was the chief reason for dispensing altogether with the photo-mechanical process in work of greater importance when producing paper currency.

The extraordinary speed with which even complicated and very dense guilloches can be executed with the aid of the new process as compared with the old one, renders it 125 possible to make a number of different trial 130

patterns very quickly by altering the relative motions of the parts of the device, and the number and distance apart of the luminous points, etc., so as to enable the most suitable pattern to be selected for the particular purpose in mind. The trial patterns may be changed much more methodically. If, for example, it turns out that in a finished pattern the space between two neighboring groups of lines is too large, the two corresponding groups of luminous spots may be shifted closer together, or new spots may be inserted, or the elegance of the pattern may be improved by shifting the eccentric of the machine. The making of a whole series of such patterns requires less time than the production of a single guilloche by the old process. Besides, by causing a number of luminous spots to operate together, graphic effects may be produced which either cannot be achieved at all with the old process or which, at best, can only be obtained in a very roundabout way with a great loss of time and with much less precision. New effects will result if the luminous spots are arranged in a crooked line instead of a straight one, or in several straight or crooked lines. New peculiar effects result if separate and distinct motions are imparted to each single group of luminous spots. All of the luminous spots or groups of them may be obscured or extinguished at short regular intervals. This will result in broken lines being produced. The breaks in the lines of the groups, if arranged in some suitable order, will produce radiating effects.

The new process also renders it possible to achieve stereoscopic effects which cannot be obtained in any other way and which, under certain conditions, constitute an almost perfect guard against counterfeits. For example a stereoscope effect may be obtained in the following manner: If the orbits of the luminous spots are photographed with two lenses placed at a certain distance apart, instead of with one lens only, and if the plane in which the luminous spots are located is periodically moved toward and from the plate, (during which operation the sensitive plate must, of course, also be moved so as to keep the image distinct), the orbits described by the points will be curves that extend in three directions. On the images thus produced with the two lenses being observed together in a stereoscopic apparatus, they will give a plastic representation of the said curves. If these two images are printed with a block in different, suitably chosen colors, *e. g.* in rainbow-style, and if a pattern of crossed lines of a suitable color and designed to baffle counterfeiters (which pattern may also be made to have plastic effects) is also impressed upon the print, then counterfeiting, either by drawn copies or by photo-mechanical means, will be impossible.

A specially simple example of a device for carrying out the new process is shown diagrammatically in Figure 1 of the drawing. Fig. 2 illustrates a guilloche produced by this device.

A clockwork or spring motor whose spring 6, situated in a spring box 5, may be wound up by a winding spindle 7, is mounted upon a fixed base plate 2 and arranged in such manner that in running down under the control of an escapement (not shown) it is caused to revolve with its casing 4 around the axis 1 of the spring that is fixed in the base plate 2. During the turning of the casing 4 a spur-wheel 9 fixed to a shaft 8 rolls around upon a toothed wheel 3 that is fixed to the rigid spring axis 1. At the upper end of the shaft 8 a crank 13 is fixed whose stud 12 engages with slot in the carriage 11, which slot extends perpendicularly to the plane of the drawing. The carriage 11 is arranged to be shifted on guide members or rails 10 arranged on the casing 4. The carriage 11 carries a box 14 in the interior of which an illuminating agent (not shown) *e. g.* a mercury vapor lamp is arranged and the top of which is closed by a plane of frosted glass 15. Above the glass an opaque screen 16 is placed into which are drilled several groups of different sized holes 17. These holes act as small luminous surfaces or spots. Above the clockwork a photographic apparatus A is arranged whose sensitive surface is adjusted with respect to the screen 16. The whole device is rigged up in a dark room. On the clockwork being caused to run down the small luminous spots execute complicated motions which are made up of the rotary motion of the clockwork casing 4 and of the linear motion of the carriage 11. By changing the wheel of the crank shaft, by altering the ratio of the speed of the shaft 8 and the casing 4 and by changing the number of luminous points or the number of plates, by changing the size and shape of the luminous points, by changing the distance of the luminous points from each other or the distances between groups of points the greatest possible variety of resultant motions and drawings may be obtained. The resultant motions may also be made up of a larger number of simple motions and of different kinds of motions than those executed with the illustrated device. The sensitive plate and the lens may also be made to execute their own motions. The arrangement may also be such that the individual groups of luminous points execute their own special motions. The luminous spots may also be caused to move in the direction vertical to the plane of their movement and their orbits may be drawn upon a sensitive plate by two lenses instead of one. All of the luminous points or groups of them may be obscured or extin-

guished at periodic intervals. Instead of producing luminous spots by means of a frosted plate and a screen, small luminous bodies such as minute incandescent lamps 5 may be used.

A special advantage of the new process, especially if it is arranged to be carried out with the aid of the stereoscopic appliances, is not only that the production of counterfeits is rendered very difficult and practically impossible, but also that attempted counterfeits can be quickly and surely detected by any unskilled person.

I claim:

15 1. A device for producing guilloches comprising means for causing a luminous spot to describe a symmetrical closed orbit corresponding to a desired guilloche, and photographic means for photographing the 20 successive positions of said spot in said orbit.

2. A device for producing guilloches, comprising means to cause a luminous spot to describe a symmetrical sinuous closed 25 orbit corresponding to a desired engine-turning, photographic means distanced from said orbit and including a lens for photographing successive positions of the spot in its orbit.

30 3. A device for producing guilloches, comprising means for producing a luminous spot, mechanism for causing said means to describe a closed geometrical path, devices to reciprocate said means during its passage 35 over said path, and photographic means to photograph successive positions of said spot in its orbit.

4. A device for producing guilloches, comprising means for producing a luminous 40 spot, mechanism for causing said means to move in a circular path, devices to reciprocate said means during its passage over said path, and means including a lens to photograph successive positions of said spot in its 45 orbit.

45 5. A device for producing guilloches, comprising means for causing a number of luminous spots to describe orbits corresponding to a desired guilloche and means

for photographing the luminous spots in the 50 said orbits.

6. A device for producing guilloches, comprising means for causing one or more luminous spots differing in shape from a circle to describe orbits varying in breadth 55 and corresponding to a desired guilloche, and means for photographing the luminous spots in the said orbits.

7. A device for producing guilloches, comprising means for producing a number 60 of luminous spots, a sensitive plate, a lens producing images of said spots upon the sensitive surface and means for moving the said images upon the surface along orbits corresponding to the lines of the desired 65 guilloche.

8. A device for producing guilloches comprising a lens, a sensitive surface, means for producing a number of luminous spots whose light impinges upon the sensitive surface, and means for causing a relative motion between the lens, the sensitive surface and the luminous spots, whereby the images of the luminous spots are moved on the sensitive surface along orbits corresponding to 70 the lines of the desired guilloches.

9. A device for producing guilloches comprising a lens, a sensitive surface, means for producing a number of luminous spots whose light impinges upon the sensitive surface, and means for moving the spots along 80 orbits corresponding to the lines of the desired guilloches.

10. Device for producing guilloches comprising, a lens, a sensitive plate, means for producing a number of luminous spots whose light impinges upon the sensitive plate, and means for moving the spots along orbits corresponding to the lines of the desired guilloches.

In testimony whereof I have signed this specification in the presence of two witnesses.

ARTHUR SCHULZE.
